UNITED STATES PATENT OFFICE.

EDWARD S. STIMPSON, OF HOPEDALE, MASSACHUSETTS, ASSIGNOR TO THE DRAPER COMPANY, OF SAME PLACE.

OIL-GUARD FOR LOOM SHEDDING-CAMS.

SPECIFICATION forming part of Letters Patent No. 664,339, dated December 18, 1900.

Application filed September 27, 1900. Serial No. 31,302. (No model.)

To all whom it may concern:

Be it known that I, EDWARD S. STIMPSON, a citizen of the United States, residing at Hopedale, county of Worcester, State of Massachusetts, have invented an Improvement in Oil-Guards for Loom Shedding-Cams, of which the following description, in connection with the accompanying drawings, is a specification, like letters on the drawings representing like parts.

This invention relates more particularly to the shedding mechanism for looms; and it has for its special object the production of means for preventing the shedding-cams from throwing oil upon the warp during the running of the loom.

The shedding-cams are usually located near the warp-beam and in their rotation they frequently throw drops of oil upon the warp, forming grease-spots, which must be later removed from the cloth. In my present invention I have provided each shedding-cam with an oil-guard which is mounted to follow the movement of the cam, the guard being interposed between the lubricating portion of the cam and the warp-beam.

Figure 1 is a cross-sectional view of a portion of the loom with one embodiment of my invention applied thereto, the warp-beam being partly shown in dotted lines; and Fig. 2 is a perspective view of one of the oil-guards shown in Fig. 1.

The cam-shaft C^X , the harness-cams C' C^2 thereon, adapted to coöperate, respectively, with suitable rolls t' t^2 on the harness-treadle T' T^2 , the harnesses H , and the warp-beam D (see dotted lines, Fig. 1) may be and are of any well-known or usual construction in looms.

Referring to Fig. 1, it will be seen that the shedding-cams are quite near the circumference of the warp-beam, and in order to prevent any oil from being thrown upon the warp by the cams I have interposed an oil-guard G between each cam and the warp-beam. In the present embodiment of my invention the guard comprises an elongated plate g , preferably provided with downturned flanges g' at its longitudinal edges, said flanges gradually being extended beyond its opposite

end and downturned, as at g^2 , each downturned portion having an open slot g^3 therein, as best shown in Fig. 2. Near its downturned portions g^2 the flanges are provided with depending ears g^4 , which, as shown in Fig. 1, straddle the treadle upon which the guard is mounted, I having herein shown the guard as fulcrumed on the pin t^X , extended through the treadle, back of its antifriction-roll, the slots g^3 receiving and straddling the projecting ends of the pin. The upper end of the guard is extended forward and upwardly and rests by its own weight against the perimeter of the cam, and obviously as the cam rotates the guard will rock on its fulcrum t^X and will follow the movement of the cam, remaining in contact with its lubricated surface. The guard is slightly concaved in the direction of its length at its upper end, as at g^5 , Fig. 2, to form a longer contacting portion with the cam, and inasmuch as the guard is directly interposed between the cam and the warp-beam no oil can be thrown from the loom. The ears g^4 , straddling the treadle as they do, prevent lateral movement of the guard, the flanges g' serving to strengthen and stiffen the latter.

So far as I am aware it is broadly new to provide an oil-guard for a rotating cam, the guard being so mounted as to follow and remain in contact with the lubricated surface of the cam, and accordingly my invention is not restricted to the precise construction and arrangement herein illustrated and described, as the same may be modified or rearranged without departing from the spirit and scope of my invention.

Having described my invention, what I claim, and desire to secure by Letters Patent, is—

1. In a loom, shedding-cams, and oil-guards therefor, mounted to follow the movement of the cams.
2. In a loom, a shedding-cam, and a movable oil-guard for and in contact with the cam.
3. In a loom, shedding-cams, treadles actuated thereby, and an oil-guard for each cam, mounted on its coöperating treadle.
4. In a loom, shedding-cams, treadles actuated thereby, and an oil-guard for each cam

pivotedly mounted on its coöperating treadle and in continuous contact with the lubricated surface of the cam.

5. A rotating cam, and an oil-guard adjacent thereto, and mounted to follow the movement of the lubricated surface thereof.

6. In a loom, the warp-beam, shedding cams, and pivotally-mounted oil-guards therefor interposed between the beam and cams

and continuously in contact with the lubricated surface of the latter.

In testimony whereof I have signed my name to this specification in the presence of two subscribing witnesses.

EDWARD S. STIMPSON.
